UNITED STATES PATENT OFFICE.

WILLIAM E. MCCORMICK, OF CHICAGO, ILLINOIS, ASSIGNOR TO INTERNATIONAL TELEPHONE MANUFACTURING COMPANY, OF CHICAGO, ILLINOIS, A CORPORATION OF ILLINOIS.

COIL-BOX FOR TELEPHONES.

SPECIFICATION forming part of Letters Patent No. 718,371, dated January 13, 1903.

Application filed May 4, 1901. Serial No. 58,722. (No model.)

To all whom it may concern:

Be it known that I, WILLIAM E. MCCORMICK, a citizen of the United States, residing at Chicago, in the county of Cook and State 5 of Illinois, have invented certain new and useful Improvements in Coil-Boxes for Telephones, of which the following is a full, clear, and exact description, reference being had to the accompanying drawings.

10 In telephones of the transmitter-arm type as heretofore generally constructed the transmitter-arms have been connected usually by hinges to suitable coil-boxes secured by screws to the wall or backboard. In such 15 construction the cast-metal box is provided with a series of exterior contact-posts, which are all exposed and in position to be easily tampered with and removed; also, the necessity of inspecting and testing the induction- 20 coil which is contained within the coil-box renders the removal of the box from its support necessary, and after it has been removed two or three times the holes in the support in which the retaining-screws take 25 become worn and the connection of the parts is rendered unstable.

The principal object of my invention is to overcome these and other objections incident to the employment of the described type of 30 coil-boxes.

Another object of my invention is to provide an improved arrangement and organization of parts, whereby the induction-coil may be more effectually and easily exposed 35 for inspection and testing and whereby one induction-coil may be readily substituted for another.

With these and other objects in view the invention includes certain particular arrangements, 40 constructions, and combinations of parts, as hereinafter fully set forth, and pointed out in the claims at the end of this specification.

In the accompanying drawings, forming a 45 part of the present specification, Figure 1 is a front view of my improved coil-box, showing the lid of the box opened and turned on its hinges to expose the interior parts. Fig. 2 is a perspective view of the coil-box of Fig. 50 1 with the lid partly swung back. Fig. 3 is

a longitudinal section of my improved coil-box with a suitable hollow transmitter-arm attached.

Referring to the drawings, the reference-letter A represents a hollow transmitter-arm 55 formed of cast metal and preferably hinged and adapted to swing vertically upon suitable pivots or trunnions which are formed on the projecting lugs b of the coil-box B. The outer end of the rocker-arm A carries a suitable transmitter of any desired type, which is not shown in detail, but is designated in general by the reference-letter T.

The coil-box B, which is secured to the wall or backboard, is preferably sectional in form 65 and is composed of a casing comprising a base-plate b', provided with suitable screw-holes for attaching the same in position, and a body b''. The base may be of skeleton or other form, but is preferably composed of a 70 rectangular plate of suitable outline and size and provided with openings to receive the usual conductors by which the windings of the coil and the transmitter are included in the circuit. This may be conveniently and 75 simply accomplished by forming the base or back plate with a suitable opening. The induction-coil I is mounted upon the base-plate, preferably by means of a supporting-frame F, which may be conveniently consti- 80 tuted of the square ends S and S' of the usual hollow wooden spool carrying the windings and a longitudinal connecting-piece S² of suitable insulating material, which carries the requisite number of binding-posts 2, 3, 4, 85 5, preferably in the form of screws. The ends S S' of the frame, which is, in effect, a yoke carrying all the parts, are secured to the base by suitable threaded bolts 6, engaging tapped holes in the base, and the secondary 90 and primary windings of the coil are connected to the binding-screws by any suitable terminals, from which they are in electrical connection with their associated parts by suitable conductors, which are not shown in the 95 drawings. By this organization and construction of parts the coil and the terminals of its windings and their associated binding-posts comprise a self-contained or unitary device which may be assembled or disassembled with 100

relation to a suitable coil-box by merely disconnecting the external conductors from the binding-posts and removing the retaining-screws 6. By this arrangement I am enabled 5 to quickly and easily change or substitute one coil for another.

The body b^2 of the coil-box is of any suitable shape adapted to inclose the coil and is preferably composed of a hollow casing, preferably of the form shown in the drawings, and provided with a surrounding flange b^3 of the same size as the base. To afford access to the interior of the box, I prefer to pivot or hinge the body thereof to the base by suitable 15 hinges b^4 at one edge, although the lid-section of the box may not necessarily comprise the entire body thereof, but may include only a portion thereof. A suitable lock b^5 is provided to engage a pin b^6 to hold the swinging 20 portion of the casing in its closed position, and the hollow transmitter-arm A is pivoted to its outer face, as above described. The swinging or hinged portion of the casing is adapted to be swung back upon its hinges to 25 afford access to the coil and the interior conductors and connections. By this arrangement the base of the box is permanently secured to the wall or backboard without the necessity of detaching the same every time 30 the parts are tested or repaired, and access to the parts is more easily obtained and they are more conveniently and effectually disclosed to the operator and more conveniently disposed for inspection and testing than here- 35 tofore.

It is obvious that various changes may be

made in the details of the device without departing from the spirit and scope of my invention. For example, the induction-coil may be supported by the body of the casing 40 instead of by the base, although I prefer the latter arrangement; also, the body may be square or of other cross-sectional shape, and instead of having the entire body swing only a portion thereof, such as a lid, may be hinged 45 to open.

Having described my invention, what I claim as new, and desire to secure by Letters Patent, is—

1. In a coil-box, the combination with a 50 base, an induction-coil supported thereon, and carrying binding-posts, of a cover hinged to the base at one side, and provided with a pivoted transmitter-arm.

2. In a coil-box, the combination with a 55 base, a frame removably supported on the base, and an induction-coil and binding-posts on the frame, of a cover for the parts comprising a hinged casing forming the body of the box.

3. In a coil-box, the combination with a 60 base b' , a frame removably carried on the base, binding-posts and an induction-coil on the frame, of a cover b^2 composed of a hollow casing having a flange, and hinges and a lock 65 between said flange and base.

In witness whereof I have hereunto set my hand in the presence of two witnesses.

W. E. McCORMICK.
